WATER COOLER

Max Alex, Alhambra, Calif., assignor to York Water Corporation, Ltd., a corporation of Nevada

Application February 13, 1933. Serial No. 656,444

15 Claims. (Cl. 62—154)

This invention has to do with coolers such as are ordinarily used in dispensing bottled water and the like, and has as its primary object the production of a cooler which is neat in appearance, is sanitary, and is easy to clean.

It is the further object of this invention to produce a cooler of the class described wherein the receptacle, in which the liquid is cooled, is non-porous, the cooling action being obtained by evaporation from a fabric or paper sheath which encloses the receptacle. In this connection, it is an important feature of this invention that the liquid evaporated from the sheath is absorbed by the sheath from a basin of waste liquid situated below the receptacle.

It is a further object of this invention to provide means associated with the receptacle for absorbing the cooling liquid during the night or while the device is cool, such means providing a supply of liquid for the sheath throughout its entire length when the surrounding atmosphere becomes warm.

The general construction of the device contemplated by this invention comprises a stand which has a shell mounted on its upper end portion, such shell being provided at its bottom portion with receptacle supporting means upon which the cooler is mounted. The cooler, or the liquid receptacle, is provided near its lower end portion with an outlet spigot, and the shell is provided with an opening through which the spigot extends.

In order to facilitate the assembly of the device and also to facilitate the removal of the receptacle for cleaning, the shell is formed so that the distance inside the shell between the front and back thereof is slightly less than the distance from the front of the spigot member to the rear of the receptacle.

It is a further feature of this invention that the spigot member is mounted a substantial distance above the bottom of the receptacle and is provided with a conduit which extends down into the bottom of the receptacle so that the coldest liquid is removed first and there is always a supply of cold liquid on hand.

It is a further object of this invention to provide a waste or drain pan which is mounted so as to facilitate its removal and which is provided with a removable drain lip.

A still further feature of this invention resides in the manner of mounting the receptacle in the shell or on the standard, such means being formed so as to positively prevent any sidewise or lateral movement of the base of the receptacle after it

has once been properly positioned within the shell.

The details in the construction of the device contemplated by this invention, together with other objects attending its production, will be best understood from the following description of the accompanying drawing which is chosen for illustrative purposes only, and in which—

Fig. 1 is a sectional elevation showing a preferred form of my invention;

Fig. 2 is a fragmentary front elevation of the device shown in Fig. 1;

Fig. 3 is a plan section taken in a plane represented by the line 3—3 in Fig. 1;

Fig. 4 is a plan section with parts broken away taken in a plane represented by the line 4—4 in Fig. 1;

Fig. 5 is a perspective view illustrating the construction of a preferred form of jar or receptacle contemplated by this invention and showing the manner in which the cooling sheath is mounted thereon; and

Fig. 6 is an inverted plan view of the receptacle shown in Fig. 5.

More particularly describing the invention as herein illustrated, reference numeral 11 indicates a stand which is shown as comprising three legs 12 interconnected by means of brace members 13 and provided at their upper ends with a receptacle support or spider made up of divergent bars 14.

A shell or cover member 15 is mounted in any suitable manner upon the upper end portion of the stand, such cover member being provided with a top 16 which has an opening 17 therein adapted to admit the reception of a jar or receptacle 18.

The jar or receptacle 18, in this form of my invention, is shown as being of glass or porcelain and is supported at its base upon the divergent bars 14, which I will hereinafter refer to as a receptacle supporting means.

For the purpose of preventing lateral or sidewise movement of the jar or receptacle 18 when it is mounted upon the supporting means 14, I provide the base of the receptacle with grooves or channels indicated in Fig. 6 by reference numeral 20. These grooves intersect in a manner corresponding to the divergent bars 14 so that when the receptacle is properly positioned within the shell the bars 14 are received in the grooves and the receptacle is held against lateral movement.

The top of the receptacle 18 is formed with an open mouth 21 which is shown as being provided

with a rubber gasket 22 upon which an inverted container 23, such as a bottle containing water, is mounted.

Reference numeral 24 indicates an outlet spigot 5 which is mounted in the bottom portion of the wall of the receptacle 18 at a substantial distance above its base.

The front of the shell 15 is provided with an opening 25 through which the spigot extends. 10 The reason for positioning the spigot at a substantial distance above the bottom of the receptacle is to always leave a quantity of cool liquid in the container after no more liquid can be withdrawn through the spigot, and, in order that the 15 coldest liquid will always be withdrawn first, I provide the spigot member with a conduit or connection generally indicated by reference numeral 26 which has its inlet opening 27 situated at the bottom of the container.

Reference numeral 30 indicates a pan or basin, 20 the shape of which is perhaps best illustrated in Figs. 3 and 4. This basin is provided with a rear flange 31 which engages a shelf or ear 32 mounted on the upper end portion of the rear leg of the stand below the receptacle supporting means 14. The front portion of the pan is made slightly deeper than the rear portion so as to give oppositely disposed raised edges 33 which are provided with flanges 34 adapted to slide over ears or 30 angles 35 which are mounted between the two forward edges of the front legs and two of the bars 14.

The parts just described provide a very convenient means for supporting the pan beneath the receptacle and permit the removal of the pan merely by a forward sliding movement. It will be observed that the pan extends forward a substantial distance so that its front portion lies beneath the spigot 24. This is to receive the waste 35 water from the spigot and in order to improve the appearance of the unit, and further to prevent splashing from the front portion of the pan, I provide a drain apron or lip 36 which has a hook flange 37 adapted to rest on the edge of the pan, and an upwardly extending rear flange 38 normally adapted to rest behind the lower edge 40 of the front portion of the skirt 15. This apron is removable by tilting the front upwardly as indicated in broken lines at 36a in Fig. 1.

In order that the spigot and the front portion of the pan will not project unduly beyond the shell, I form the shell as indicated in Figs. 3 and 4 with a front panel 15f which is curved rearwardly.

It will be understood that, in the use of a cooler of this character, there is always a certain amount of water in the pan 30, and I propose to take advantage of this fact to provide an efficient means for cooling the receptacle 18. This is accomplished by providing the receptacle with a sleeve or sheath 39 which surrounds the major portion of the receptacle and has a downwardly projecting portion 39' which extends into the liquid in the pan 30. This sleeve or sheath is formed of paper or other suitable absorbent material which will, by capillary action, carry water to the surface of the receptacle contacted by the sheath. The evaporation of such water will be attended by an absorption of heat from the receptacle, thus cooling its contents.

I have found in actual use of a device of this character that the mere capillary action of the sheath itself, especially when the room temperature is moderately high, will not be effective to wet the outer surface of the receptacle through-

out its entire length. In this connection, I have devised a novel means for storing moisture at intermediate points throughout the length of the receptacle during the cooler hours of the day, such moisture being absorbed by the sheath as the room temperature increases so as to keep the entire length of the sheath damp at all times. These moisture storage means, which I may term reservoirs, are shown as comprising channels or grooves 40 positioned along the length of the receptacle and filled with water absorptive material such as felt or paper.

In the operation of the device, therefore, the sheath will, through its capillary action during the cooler periods of the day, carry the water from the pan 30 to the various pads 41 which absorb the water and become saturated. Then when the temperature becomes higher and the rate of evaporation from the sheath exceeds the rate at which moisture is absorbed by the sheath from the pan, the liquid which saturates the pads 41 will be absorbed by the sheath 39 so as to keep the same wet thus maintaining the cooling action throughout the entire length of the receptacle when it is most needed.

The bottom portion of the sheath is provided with notches indicated at 42 to pass the brace members 14, and the front portion of the sheath is provided with an elongated notch 43 which receives the spigot 24 and which incidentally provides a means for supporting the sheath on the receptacle.

The top of the shell 15 is provided with openings 44, and, since the bottom of the shell is open, this permits the free circulation of the air about the wet sheath on the receptacle so as to aid in the evaporation of the moisture from the sheath.

To facilitate the removal of the jar or receptacle from the shell for the purpose of cleaning the same, etc., I form the receptacle of a size such that the combined width of the receptacle and the spigot is less than the internal distance between the front and rear of the shell. This permits the removal of the receptacle in the manner indicated by the dot and dash line position 17a in Fig. 1.

It is to be understood that, while I have herein described and illustrated one preferred form of my invention, the invention is not limited to the precise construction as described above, but includes within its scope whatever changes fairly come within the spirit of the appended claims.

I claim as my invention:

1. A liquid cooler embodying: a receptacle having a recess in its outer surface; liquid absorbing means in said recess; a liquid absorbent sheath mounted on said receptacle and engaging said first mentioned absorbing means; and means for supplying a liquid to said sheath.

2. A liquid cooler embodying: a receptacle having a recess in its outer surface; supporting means for said receptacle; a liquid container mounted in said support below said receptacle; liquid absorbing means in the recess in said receptacle; and a liquid absorbent sheath mounted on said receptacle and engaging said first mentioned liquid absorbing means; said sheath having a portion thereof contacting a liquid in said container.

3. A liquid cooler embodying: a jar having annular recesses in vertically spaced relation with the bottom thereof; supporting means for said jar; liquid absorbent pads in said recesses; a liquid container mounted in said supporting

- means below said jar; and a liquid absorbent sheath enclosing said jar and engaging said pads, said sheath having a bottom portion extending into a liquid in said liquid container. 80
5. 4. A liquid cooler embodying: a jar having annular recesses in vertically spaced relation with the bottom thereof; supporting means for said jar; liquid absorbent pads in said recesses; a liquid container mounted in said supporting means below said jar; a liquid absorbent sheath enclosing said jar and engaging said pads, said sheath having a bottom portion extending into a liquid in said liquid container; and cover means for said jar. 85
15. 5. A water cooler of the class described embodying: a stand; a receptacle support in the top of said stand; a liquid receptacle on said receptacle support; an inverted liquid container mounted in the top of said receptacle; ears in the top of said stand below said support; a pan slidably supported by said ears; and a water absorbent sheath enclosing said receptacle and extending into said pan. 90
20. 6. A water cooler of the class described embodying: a stand; a receptacle support in the top of said stand; a liquid receptacle on said receptacle support; an outlet spigot mounted in the bottom portion of said receptacle; an inverted liquid container mounted in the top of said receptacle; ears in the top of said stand below said support; a pan slidably supported by said ears; a water absorbent sheath enclosing said receptacle and a shell mounted on the top of said stand and adapted to enclose said receptacle, said shell being formed of an internal diameter greater than the distance from the end of said spigot to the back of said receptacle. 100
30. 7. A water cooler of the class described embodying: a stand; a receptacle support in the top of said stand; a liquid receptacle on said receptacle support; an outlet spigot mounted in the bottom portion of said receptacle; an inverted liquid container mounted in the top of said receptacle; and a cover for said receptacle mounted on the top of said stand, said cover comprising a shell having an opening for said spigot and having an internal diameter greater than the distance from the end of said spigot to the back of said receptacle. 105
40. 8. A water cooler of the class described embodying: a stand; a receptacle support in the top of said stand; a liquid receptacle on said receptacle support; an outlet spigot mounted in the bottom portion of said receptacle; ears in the top of said stand below said support; a pan slidably supported by said ears; and a cover for said receptacle mounted on the top of said stand, said cover comprising a shell having an opening for said spigot and having an internal diameter greater than the distance from the end of said spigot to the back of said receptacle. 110
45. 9. A water cooler of the class described embodying: a stand; a receptacle support in the top of said stand; a liquid receptacle on said receptacle support; an outlet spigot mounted in the bottom portion of said receptacle; ears in the top of said stand below said support; a pan slidably supported by said ears; and a cover for said receptacle mounted on the top of said stand, said cover comprising a shell having an opening for said spigot and having an internal diameter greater than the distance from the end of said spigot to the back of said receptacle. 115
50. 10. A water cooler of the class described embodying: a stand; a receptacle support in the top of said stand; a receptacle on said support; means for delivering a liquid into said receptacle; a forwardly extending spigot in the bottom portion of said receptacle; pan supporting means in the top of said stand below said receptacle support; a pan removably mounted on said pan supporting means, said pan having a forwardly extending portion positioned below said spigot; and a drain lip removably mounted in the extending portion of said pan below said spigot. 120
55. 11. For use in a cooler of the class described: a receptacle having a plurality of channels in its outer surface; absorbent pads in said channels; and an absorbent sheath surrounding said receptacle and engaging said absorbent pads. 125
60. 12. For use in a cooler of the class described: a receptacle having a plurality of channels in its outer surface; absorbent pads in said channels; a spigot mounted in the wall of said receptacle; and an absorbent sheath surrounding said receptacle and engaging said absorbent pads, said sheath being provided with a notch adapted to pass said spigot and engage said spigot at its upper end to support said sheath. 130
65. 13. A water cooler of the class described embodying: a stand; a shell mounted on the top of said stand; a receptacle support in the bottom of said shell; a receptacle mounted on said support in said shell; and an outlet spigot mounted in said receptacle and projecting through an opening in said shell, the distance between the front of said spigot and the back of said receptacle being less than the internal distance between the front and back of said shell. 135
70. 14. A water cooler of the class described embodying: a stand; a set of divergent bars in the top of said stand; and a receptacle mounted in said bars, the bottom of said receptacle being provided with grooves to receive said bars. 140
75. 15. A water cooler of the class described embodying: a stand; a set of divergent bars in the top of said stand; and a receptacle mounted on said bars, the bottom of said receptacle being provided with shoulders adapted to engage said bars and hold said receptacle against turning relative to said stand. 145
